C. F. BETZ

ICE CREAM CONE

Filed Nov. 14, 1927

Inventor:
Charles F. Betz,

By S. S. Denby
Attorney.

UNITED STATES PATENT OFFICE.

CHARLES F. BETZ, OF ST. LOUIS, MISSOURI, ASSIGNOR TO AMERICAN CONE & PRETZEL COMPANY, OF PHILADELPHIA, PENNSYLVANIA, A CORPORATION OF WEST VIRGINIA.

DESIGN FOR AN ICE-CREAM CONE.

Application filed November 14, 1927. Serial No. 24,122. Term of patent 7 years.

To all whom it may concern:

Be it known that I, CHARLES F. BETZ, a citizen of the United States, residing in the city of St. Louis, county of St. Louis, and State of Missouri, have invented a new, original, and ornamental Design for an Ice-Cream Cone, of which the following is a specification, reference being had to the accompanying drawing, forming part thereof.

The figure is a perspective view of an ice cream cone showing my new design.

I claim:

The ornamental design for an ice cream cone as shown.

In testimony whereof I have hereunto set my name this 5th day of November, 1927

CHARLES F. BETZ.
